(57) **CLAIM**

The ornamental design for a vehicle steering wheel as shown and described.

DESCRIPTION

FIG. 1 is a rear view of a vehicle steering wheel according to the new design;

FIG. 2 is a front view thereof;

FIG. 3 is a right side view thereof;

FIG. 4 is a left side view thereof;

FIG. 5 is a top view thereof;

FIG. 6 is a bottom view thereof;

FIG. 7 is a top, rear, right side perspective view thereof; and, FIG. 8 is a top, rear, left side perspective view thereof shown on a vehicle that is shown in broken lines.

The broken lines illustrate portions of the vehicle steering wheel that form no part of the claimed design. The vehicle shown in broken lines is for illustrative purposes only and forms no part of the claimed design.
